UNITED STATES PATENT OFFICE.

THOMAS BRADY, OF EAST ORANGE, NEW JERSEY, ASSIGNOR, BY MESNE ASSIGNMENTS, TO OTIS ELEVATOR COMPANY, OF NEW YORK, N. Y., A CORPORATION OF NEW JERSEY.

LEVER LATCH.

Application filed September 18, 1923. Serial No. 663,343.

This invention relates to a novel lever latch of simple construction.

The invention has been particularly worked out in connection with closures for elevator hatchway doors. As is well known, it is very essential that such doors be locked in closed position when the elevator car is not located at the landing or level at which the doors are located and, furthermore, it is essential that this locking mechanism be releasable only from the elevator side of the door and not from the floor level.

This invention has for its salient object to provide a lever latch which is adaptable for example to an operating lever for elevator hatchway doors and which is so constructed and arranged that the door will be automatically locked by the door operating lever when the door has been closed thereby.

Another object of the invention is to provide lever locking mechanism so constructed and arranged that movement of the lever in one direction will automatically release the lock.

Another object of the invention is to provide a door closure having lever operating means with locking mechanism engageable with the lever and releasable only from the elevator side of the door, although means may be provided for opening the door from the outside by the use of a key. This locking mechanism operates during the closing travel of the door and before the door is fully closed.

Further objects of the invention will appear from the following specification taken in connection with the drawings, which form a part of this application, and in which

Fig. 1 is an elevational view of a hatchway door having lever operating mechanism and locking means for locking the door in closed position.

Fig. 2 is an enlarged detail view of the locking mechanism.

Fig. 3 is an elevational view similar to Fig. 1, but showing another form of the locking mechanism.

Fig. 4 is an enlarged detail elevation of the locking mechanism shown in Fig. 3.

Fig. 5 is a detail view on an enlarged scale showing another form of locking mechanism, this mechanism being shown in locking position.

Fig. 6 is a view similar to Fig. 5, but showing the lever and locking means in unlocked position, and

Fig. 7 is a sectional elevation taken at right angles to Fig. 5.

The invention briefly described comprises lever operating mechanism such as is used for opening and closing elevator hatchway doors and locking means for the lever consisting of a keeper mounted on the door and through which the lever is slidable, the lever and keeper having means adapted to cooperate in locking the lever and door in closed position and further means adapted to cooperate to release the lock when the lever is swung in a direction to open the door. In the particular embodiment of the invention shown, the cooperating means on the lever and keeper comprise abutments on the keeper for engagement with notches in the lever and further abutments on the keeper disposed at the opposite side of the lever for swinging the keeper in a manner to release the locking abutment from engagement with the lever notch when the lever is swung in a direction to open the door. Further details of the invention will appear from the following description.

This application is a continuation in part of application Serial No. 335,542 filed November 3rd, 1919, in which application the lever locking mechanism illustrated in Figs. 1 and 2 is disclosed which was issued March 11, 1924 as Patent No. 1,486,278.

Referring, first, to the embodiment of the invention shown in Figs. 1 and 2, the door comprises in this instance two movable panels 10 and 11 and a stationary panel 12. In devices of the type under consideration, the panel 10 is termed the fast moving panel and the panel 11, the slow moving panel.

The hatchway door illustrated is operated to open and closed position by means of a lever 13 and as far as the locking mechanism is concerned, this lever may be operated manually or by suitable power operating means, such as power cylinders 14 and 15 operating on opposite sides of the lever through a pivoted arm 16. The lever 13 is pivoted at 17 to a base 18 and fluid operating means is introduced into the power cylinders through suitable conduits 19 and 20. This power operating means for the lever will

not be further described in this application since it forms no part of the present invention and is fully disclosed in Patent No. 1,486,278 above referred to.

5 The lever locking mechanism and, therefore, the door locking mechanism comprises a keeper 25 pivoted at 26 to a bracket 27 secured to the panel 10. This keeper has a slot therein through which the lever 13 extends and is slidable. The keeper also is provided at one side of its pivot with a pair of abutments or rollers 28 and 29 and on the opposite side of its pivot 26, the keeper has mounted therein an abutment or roller 10 15 30.

In the form of the invention shown in Figs. 1 and 2, the roller 30 is adapted to coact with a notch 31 formed in the lever 13.

The construction shown in Figs. 1 and 2 20 operates as follows. When the lever 13 is swung manually or by power in an anti-clockwise direction, the door will be closed and when the door reaches closed position, the abutment or roller 30 will engage the 25 notch 31 of the lever. This engagement will effectively prevent any opening of the hatchway door from the floor level since an attempt to slide the door will be forestalled by the engagement of the roller 30 in the 30 notch 31. When the operator desires to open the door, the lever is swung in a clockwise direction manually or by power and the initial movement of the lever in this direction will swing the keeper 25 about its pivot 26 35 due to the engagement of the lever with the roller 28. This swinging movement of the keeper will release the roller 30 from the notch 31 of the lever thereby permitting the lever to be swung in a clockwise direction 40 about its pivot to open the door. In Figs. 1 and 2, the two notches 31 and 32 are shown in the lever so that in case the roller 30 is not properly positioned for engagement with the notch 31 it will engage the notch 32.

45 Referring to the embodiment of the invention illustrated in Figs. 3 and 4, a two panel door is illustrated comprising panels 40 and 41. These doors are operated by a lever 42 pivoted at 43 on a base 44. The lever 42 may be operated manually or by power and the particular form of the invention shown in Fig. 3 is adapted for operation by power such as springs (not shown) acting through a quadrant arm 45, which is geared 50 to a sector 46 carried by the lever. A dash pot 47 is disposed on the opposite side of the lever for cushioning the door movement.

In this embodiment of the invention, a keeper 48 similar to the keeper 25 is provided and keeper 48 is pivoted at 49 to a plate 50 mounted on the door section or panel 40. The keeper has mounted therein at one side of its pivot, an abutment 51 engageable with one of a plurality of notches 52 formed in the lever and at the opposite

side of its pivot, the keeper has an elongated abutment 53 engageable by the lever in its door opening movement to release the abutment 51 from the lever notch. This construction operates in a manner exactly similar to that already described.

55 Referring now to the embodiment of the invention illustrated in Figs. 5, 6 and 7, this form of the invention does not differ materially from the embodiments already described and comprises a lever 60 having an operating handle 61, a keeper 62 pivoted at 63 to a bracket 64 carried by a door panel 65.

The keeper 62 has a pair of rollers 66 and 67 disposed at one side of its pivot and a roller 68 disposed at the opposite side thereof. When the lever is moved to the position shown in Fig. 5 and the door is closed, the roller or abutment 66 will be positioned in a notch 69 formed in one edge of the lever. In order to insure the positioning of the keeper 62 in such a manner as to dispose the roller 66 and the notch 69, a lug 70 is clamped to the lever by a screw 71 and a set screw 72 in the proper position to tilt the keeper 62 to the position shown in Fig. 5 when the door is in closed position.

70 In order to open the door the lever 60 is swung in a clockwise direction and due to its engagement with the roller 68 of the keeper, the lever will tilt the keeper until the line connecting the center of the keeper to the pivot 63 and the center of the roller 68 is disposed at right angles to the lever as shown in Fig. 6. The roller 66 will thereupon be released from the notch 69 of the lever, permitting free movement of the lever to open the door.

75 From the foregoing description it will be seen that simple, practical and efficient mechanism has been provided for latching operating levers which when applied to the lever of a door actuating mechanism will insure the locking of doors of the type described. It will be evident that the door will be automatically locked and automatically released by the actuation of the door operating lever and that no additional operations are necessary to lock or unlock the door.

80 Although certain specific embodiments of the invention have been particularly shown and described, it will be understood that the invention is capable of modification and that changes in the construction and in the arrangement of the various cooperating parts 85 may be made without departing from the spirit or scope of the invention, as expressed in the following claims.

85 What I claim is:

1. A lever fulcrumed at one end, a member movable by the lever, a keeper pivoted on said member slidably receiving said lever, said keeper having means disposed on opposite sides of its pivot for engaging the lever to latch said movable member and for 130

engaging the lever to tilt the keeper relative to the lever and unlatch the lever from the keeper.

2. A lever fulcrumed at one end, a member 5 movable by the lever, a keeper pivoted on said member slidably receiving said lever, said keeper being tiltable on its pivot to latching and unlatching position with respect to said lever and means on the keeper 10 engageable with opposite sides of said lever to tilt the keeper relative to the lever as the lever is swung about its fulcrum.

3. In combination, a sliding door, a keeper pivoted on the door, a door operating lever 15 pivoted at a point remote from the pivot of the keeper, said lever having a slidable engagement with the keeper and being constructed with a notch in one of its edges, said keeper having a means disposed on one side 20 of its pivot and on the notched side of the lever for engaging the notch in the lever to cause the lever to hold the door against sliding, said keeper having another means on the other side of its pivot and on the opposite 25 side of the lever for engaging the lever and for causing the movement of the lever to tilt the keeper relative to the lever out of engagement with the notched side of the keeper.

4. In combination, a sliding door, a keeper 30 pivoted on the door, a door operating lever pivoted at a point remote from the pivot of the keeper, said lever having a slidable engagement with the keeper and being constructed with a series of spaced notches in 35 one of its edges, said keeper having a means disposed on one side of its pivot and on the notched side of the lever for engaging the notches in the lever to cause the lever to hold the door against sliding, said keeper having 40 another means on the other side of its pivot and on the opposite side of the lever for engaging the lever and for causing the movement of the lever to tilt the keeper relative to the lever out of engagement with the 45 notched side of the keeper.

5. In combination, a sliding door, a keeper

pivoted on the door, a door operating lever pivoted at a point remote from the pivot of the keeper, said lever having a slidable engagement with the keeper and being constructed with a notch in one of its edges, 50 said keeper having a means disposed on one side of its pivot and on the notched side of the lever for engaging the lever to cause the movement of the lever in one direction to 55 slide the door to closed position and to engage the notch in the lever when the door is closed to cause the lever to hold the door against sliding in the opposite direction and said keeper having another means on the 60 other side of its pivot and on the opposite side of the lever for engaging the lever and for causing the movement of the lever in the other direction to tilt the keeper relative to the lever out of engagement with the 65 notched side of the lever and to slide the door to open position.

6. In combination, a sliding door, a keeper pivoted on the door, a door operating lever pivoted at a point remote from the pivot 70 of the keeper, said lever having a slidable engagement with the keeper and being constructed with a series of spaced notches in one of its edges, said keeper having a means disposed on one side of its pivot and on the 75 notched side of the lever for engaging the lever to cause the movement of the lever in one direction to slide the door to closed position and to engage one of the notches in the lever when the door is closed to cause the lever 80 to hold the door against sliding in the opposite direction and said keeper having another means on the other side of its pivot and on the opposite side of the lever for engaging the lever and for causing the movement of 85 the lever in the other direction to tilt the keeper relative to the lever out of engagement with the notched side of the lever and to slide the door to open position.

In witness whereof, I have hereunto set 90 my hand this 17 day of Sept., 1923.

THOMAS BRADY.
